UNITED STATES PATENT OFFICE.

ALBERT E. VAUGHN, OF LOS ANGELES, CALIFORNIA.

METHOD OF MAKING SIGNS.

Application filed June 21, 1926. Serial No. 117,417.

My invention relates to painted or lacquered signs, a purpose of my invention being the provision of an extremely simple, rapid and inexpensive method of making 5 painted or lacquered signs by which characters and backgrounds of any color combination can be produced. My method is particularly adapted, although not necessarily, for making all lacquered signs, the 10 durability of which over painted signs and the relatively low cost thereof as against baked enamel signs is well recognized by those skilled in the art, but the making of which has never been accomplished hereto- 15 fore with any degree of commercial success.

I will describe only one method of making signs embodying my invention and will then point out the novel features thereof in claims.

20 In the accompanying drawings,

Figures 1, 2 and 3 are views showing in plan a sign board and illustrating the several steps of the method embodying my invention necessary to the making of a sign.

25 In carrying out my invention I provide a sign board 15 formed of suitable material such as sheet metal and upon one surface of which is applied the coats of paint or lacquer necessary to the making of a sign. 30 The first step in the method is to cover the surface with a coat of paint or lacquer of any desired color to form a background 16. By scribing lines on the background after it is dry, characters 17 of any kind, such as

35 letters L and T, can be blocked or outlined on the background, together with a rectangular border 18 formed in surrounding relation to the letters. If it is desired to color the background different from the letters 40 and border, a suitable masking paste 19 is applied to the letters and border to completely cover them, as illustrated in Figure 1. The character of the masking paste is such as to be impervious to paint or lacquer

45 and very slow to dry in order that it may retain its pasty state to permit removal thereof from the surface when desired.

Having applied the masking paste as described, the next step is to apply paint or lacquer of the desired color for the background and preferably through the medium of an air brush, so as to completely cover the entire surface of the board, as illustrated in Figure 2. In applying the paint or lacquer in this manner, it is directly applied to the background surface, but superimposed

on the masking paste so that it cannot adhere to the surface of the letters and border. After the paint or lacquer has dried (in the case of lacquer the drying is very rapid) the 60 masking paste is now wiped from the surface of the board, as illustrated in Figure 3, and as that portion of the paint or lacquer covering the letters and border is superimposed on the masking paste it will be clear 65 that as the result of the wiping operation the paint or lacquer is removed from the letters and border, leaving the dried paint or lacquer on the background surface. In this manner, the background is painted or lacquered in one color while the letters and border are painted or lacquered in another 70 color.

A suitable masking paste for use in connection with my improved method may be 75 constituted as follows: Glycerine, one and one-half parts, glucose one-half part, lithopone three parts, graphite one and one-half parts, and water one-half part. The glycerine is added for the purpose of maintaining 80 a state of fluidity, the glucose for the purpose of lending viscosity to the mixture, the lithopone constitutes the body, the graphite lends color, and the water serves to reduce the mixture to a proper consistency. To the 85 above elements I may also add any suitable emulsion which will facilitate the application of the mixture to a surface by means of a brush.

It will, of course, be understood that the 90 method just described is capable of adaptation to the making of letters and a border of a color different from the original color of the background, and that the background is permitted to maintain its original color. 95 This can be readily accomplished by covering the background with the masking paste, so as to leave the letters and border exposed for the direct application of paint or lacquer thereto so that when the masking paste is removed the paint or lacquer will be removed only from the background and not from the letters and border.

The method practised as described permits 105 the formation of an all-lacquer sign in which the letters or the characters and background can be formed rapidly, symmetrically and with a uniform distribution of lacquer to each surface, thus producing a sign of superior beauty and durability.

Should the masking paste not be uniformly 110 distributed over the surface of the sign-

board so as to produce thin spots therein, there is a possibility of the paint or lacquer penetrating the masking paste and thus adhering to the background. I overcome this 5 objection by spraying powdered aluminum or other suitable material on the paste before applying the paint or lacquer, thus forming a metal coat which prevents the paint or lacquer penetrating the paste and thus insures ready removal of the paint or lacquer 10 when desired.

From the foregoing description, taken in conjunction with the accompanying drawings, it will be manifest that I have provided a method of making signs which essentially consists in the successive application to a surface of coats of paint or lacquer of different colors in a manner to permit each coat to dry before applying the next 20 coat, superimposing the coat of masking paste on each coat of paint or lacquer before applying a succeeding coat, and removing each coat of masking paste together with those portions of the superimposed paint or 25 lacquer coat which have not adhered to the sign surface, whereby predetermined portions of each paint or lacquer coat are caused to adhere to the sign surface in the production of sign characters and a background of different colors.

Although I have herein shown and de-

scribed only one method of making signs embodying my invention, it is to be understood that various changes and modifications may be made therein without departing from the spirit of the invention and the 35 spirit and scope of the appended claims.

I claim as my invention:

1. A method of making signs which consists in covering a surface with a background 40 of a given color, superposing characters on the background formed of a slow drying masking paste which is impervious to paint after the background color is dry, thereafter super-posing a coating of paint on the background and characters, allowing the final coat of paint to dry, and finally removing the masking paste for providing characters of the color previously obscured by the paste.

2. The method of making signs which consists in coating a surface with a lacquer of a given color to provide a background, allowing the background color to dry, painting characters on the background with a slow-drying masking paste, which is impervious 50 to lacquer, coating the background and characters with lacquer, allowing the final coat of lacquer to dry, and finally removing the masking paste for providing characters of the colors previously obscured by the paste. 55

ALBERT E. VAUGHN.
